UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

SENDING ARRANGEMENT.

Application filed September 3, 1921, Serial No. 498,419, and in Germany September 26, 1918.

(GRANTED UNDER THE PROVISIONS OF THE ACT OF MARCH 3, 1921, 41 STAT. L., 1313.)

German Patent 304361 discloses a sender arrangement in which special means are provided for preventing the radiation of harmonics produced in the generator. The 5 main patent refers to the case of a cathode tube sender in which the harmonics have particularly disturbing effects if the antenna as an energized circuit is connected direct with the tubes. Practical experience has 10 shown that all other generators of undamped oscillations, such as arc lamps, high frequency machines, etc., send out harmonics through known circuits and cause disturbances in the modern, highly sensitive receiving arrangements.

In accordance with the invention, the special protecting circuits disclosed in the main patent are applied also to such generators. The arrangement is applicable to 20 circuits in which the generator is connected direct with the main circuit (antenna), and also to circuits in which the generator affects an alternating current resistance provided in the main circuit (antenna).

25 Figs. 1, 2 and 3 of the drawing represent such circuit arrangements, in which a protecting circuit S tuned to the main oscillation is connected in parallel with the antenna. The generator, arc lamp, or high frequency machine is connected at G.

This simple arrangement for preventing the radiation of undesirable harmonics is particularly advantageous. The trap S has practically an infinite impedance to the

main or carrier frequency and almost as 35 great impedances to the side band frequencies which, of course, are always close to the carrier frequency.

Thus the carrier and side band frequencies will be transmitted while the undesirable 40 frequencies which are quite different from the carrier frequency will find a comparatively easy path thru the trap S and hence will not be transmitted.

Having described my invention, I claim: 45

1. In a radio transmitting apparatus, an antenna system, a source of a plurality of frequencies coupled thereto and means for absorbing oscillations it is desired not to transmit comprising solely a trap for the 50 oscillations it is desired to transmit and means for coupling said trap directly to said antenna system.

2. In a transmitting apparatus, an antenna system, a source of a plurality of frequencies coupled thereto, and means for absorbing the frequencies it is desired not to transmit comprising a circuit having a high impedance for the frequency it is desired to transmit, the impedance of said circuit for 55 other frequencies gradually decreasing with increase in the difference in frequency from the frequency it is desired to transmit and means for connecting said absorbing means directly to said antenna system. 60 65

In testimony whereof I affix the signature.

ALEXANDER MEISSNER.
